UNITED STATES PATENT OFFICE.

EDGAR B. STOCKING, OF WASHINGTON, DISTRICT OF COLUMBIA; SARAH C. STOCKING
EXECUTRIX OF SAID EDGAR B. STOCKING, DECEASED.

CLOTHES-WRINGER.

1,252,311.

Specification of Letters Patent.

Patented Jan. 1, 1918.

Application filed December 14, 1916. Serial No. 137,017.

To all whom it may concern:

Be it known that I, EDGAR B. STOCKING, a citizen of the United States, residing at Washington, in the District of Columbia, 5 have invented certain new and useful Improvements in Clothes-Wringers, of which the following is a specification, reference being had therein to the accompanying drawing.

10 This invention relates to certain new and useful improvements in automatic pressure releasing means for rotating pressing members such as clothes wringers, mangles, and the like, the object being to provide means 15 for automatically and positively separating the rolls in case of over feeding of material, injury to the hands of the operator, or the entrance of a foreign object between the same.

Another object of my invention is to provide an automatic releasing means in which a mechanism is provided for instantaneously and positively shutting off the power simultaneously with the operation of the releasing means, whereby the rolls are instantaneously separated and the rotation thereof stopped so as to prevent the foreign object, or other cause actuating the release, 25 from being further drawn between the rolls.

Another and further object of the invention is to provide an automatic pressure releasing device in which the meshing gears of the rotating pressure rolls are thrown out of mesh simultaneously with throwing off the power and the releasing of the pressure 35 in order to allow the clothes wound upon either roll to be unwound therefrom by simply pulling on the clothes thereby overcoming the difficulties now existing in machines of this character in having to reverse the 40 movement of the rolls to remove the clothes therefrom.

Another and further object of the invention is to provide a pressure roll release which is provided with means for manually 45 releasing the pressure whereby the operator can at any time desired instantaneously release the pressure and shut off the power.

Another and further object of the invention is to provide a machine which is so constructed that the same can be operated as an ordinary machine of this character by providing means for locking the elements involved in such positions that the automatic

and manual releasing mechanism is prevented from being operated.

Another and still further object of the invention is to provide a pressure roll release which is exceedingly simple and cheap in construction and one which is especially adapted to be used in connection with clothes wringers in order to instantaneously and simultaneously release the pressure, 55 separate the pressure rolls and shut off the power so as to instantaneously stop the rotation of the rolls to prevent the foreign 60 object from being drawn further between the same.

Another object of the invention is to provide an automatic pressure releasing device in which the rolls can be held in separated 70 position and the pressure adjusted to enable the machine to wring blankets and other thick goods, the upper roll when the parts are in this position being driven by 75 tension of the goods passing between the rolls.

Other and further objects and advantages of the invention will be hereinafter set forth and the novel features thereof defined by the appended claims.

80 In the accompanying drawings,

Figure 1 is a side elevation partly in section of my improved construction of automatic pressure release showing the application of the same to a clothes wringer of the ordinary construction now in use;

Fig. 2 is an end view, the driving member being removed;

Fig. 3 is an enlarged vertical section through one of the side bars showing the 90 springs employed for positively separating the rolls when the pressure is released;

Fig. 4 is a horizontal section taken on line 4—4 of Fig. 3;

Fig. 5 is a perspective view of the operating and trip member detached;

Fig. 6 is a perspective view of the spring catch;

Fig. 7 is a side elevation partly in section showing the pressure rolls separated and 100 the power cut off;

Fig. 8 is a detail side elevation of a slightly modified form of releasing member constructed to be used in connection with a clothes wringer having the pressure roll 105 gears arranged on the outside of the frame;

Fig. 9 is a detail view of a slightly modified form of bearing, and

Fig. 10 is a detail section showing a slightly modified form of adjusted tension of the contracting springs.

Like numerals of reference refer to like parts in the several figures of the drawings.

In the drawings I have shown my improved construction of automatic pressure release applied to an ordinary wringer comprising a frame 1 having slotted side bars 2 provided with bearings 3 in which is mounted the shaft 4 of the lower pressure roll 5 which is extended as shown at 5' and is adapted to be driven by any suitable means as will be hereinafter fully described. Mounted in the frame above the lower pressure roll 5 is an upper pressure roll 6 provided with a shaft 7 carrying bearings 8 on which are mounted coil pressure springs 9 engaged by bearing plates 10 carried by a pressure bar 11, said bearings and pressure springs working in grooves formed in the opposing faces of the slotted side bars in order to guide and hold the bearing and pressure springs in position within the slotted side bars in their vertical movement therein. The upper ends of the slotted side bars are cut away to form shoulders to provide a seat for a movably mounted top bar 12 which is provided with the usual threaded boxes 13 carrying pressure screws 14 engaging the bearing plates 10 carried by the pressure bar 11 so as to adjust the pressure on the upper pressure roll.

The pressure roll carrying shafts 4 and 7 are provided with the usual meshing gears 6' at each end of the rolls 5 and 6 inclosed by gear casings 6² which are connected to the pressure springs by arms 6³ in the usual manner.

The walls of the grooves formed in the opposing faces of the slotted side bars are slotted as shown at 15 which slots communicate with vertical bores 16 formed in the side bars at each side of the slot as clearly shown in Figs. 3 and 4. The bearings 8 are provided with depending lug portions embracing the upper pressure roll shaft 7 having openings formed therein through which is adapted to be forced a pin 17 which is provided with a cut-out portion 18 forming shoulders for preventing the longitudinal movement of the pin after the same has been inserted, the upper edge of the pin being provided with a semi-circular recess 19 to receive the shaft 7 so as to securely lock the depending legs of the bearing in position on the shaft.

In order to provide positive means for raising the upper pressure roll so as to separate the rolls when the pressure is released as will be hereinafter fully described, I arrange within the upper portions of the bores 16 contraction springs 20, the lower ends of

which embrace the outwardly projecting end portions of the pin 17 and are seated in notches formed therein and the upper ends carry stirrups 21 through which extend adjusting screws 22 carried by plates 23 mounted on the top of the side bars 2. Arranged within the stirrups on the adjusting screws 22 are nuts 24, the corners of which are embedded within the walls of the bores 16 so as to prevent the nuts from turning when the screws are adjusted, and it will be seen that by this construction the tension of the springs can be adjusted. In order to aid the lifting springs 20 in raising the parts of the wringer arranged above the upper pressure roll, I arrange in the lower portions of the bores 16 expansion springs 25 which are provided with bearing plugs 26 at the upper ends engaging the ends of the pin 17, the lower ends of the expansion springs 25 being mounted on adjusting screws 27 as clearly shown in Fig. 3 in order to adjust the tension of the springs.

It will be seen by this construction that I have provided each of the side bars of the wringer frame with expansion and contraction springs arranged to lift the upper pressure roll and the movable parts above the same when the pressure is released so as to positively separate the rolls. In applying the construction to some forms of wringers, I have found that it is only necessary to employ one pair of springs for raising the upper pressure roll and the movable parts, and I do not wish to limit myself to the use of two sets of springs for accomplishing this result as either set can be eliminated and the same result obtained, the two sets of springs being only used when my improved construction of pressure release is applied to a heavy wringer in which the weight of the movable members above the upper pressure roll is such that it is necessary to provide additional means in connection with one set of springs to raise the movable parts.

Secured to the ends of the top bar 12 are spring catches 28 carrying beveled face catch lugs 29 adapted to engage keeper pins 30 extending across the slots of the side bars so as to hold the top bar in predetermined position on the frame in order to allow the pressure screws to be adjusted in the ordinary manner for adjusting the pressure on the pressure rolls. Arranged above the keeper pins 30 are stop pins 31 adapted to be engaged by the catch lugs 29 in their upward movement when they have been thrown off of the keeper pins 30 so as to limit the upward movement of the top bar and hold the same rigidly within the wringer frame to allow the pressure screws to be adjusted when the rolls are separated so that blankets or heavy clothes can be operated upon as shown in Fig. 7.

Mounted on the outer ends of the shaft 13

7 of the upper pressure roll 6 are operating members 32 and 33 provided with serrated portions 34 engaged by the serrated portions 35 of trip members 36 and locked in their 5 adjusted position by bolts 37, said trip members having inclined faces 38 adapted to engage the outwardly projecting curved lower ends 39 of the spring catches 28 so as to move said spring catches outwardly when 10 brought into engagement therewith in order to move the catch lugs out from under the keeper pins 30 to release the top bar when the pressure rolls are separated beyond the 15 distance of ordinary movement in the passage of a proper thickness of clothes therethrough. As the upper rolls 6 are separated by a foreign object or by an over-thick feeding of clothes being drawn between the pressure rolls the trip members 20 release the spring catches which instantaneously releases the pressure means and the separating springs lift the upper roll into such position that the foreign object, over-fed clothes or hand of the operator are prevented from being drawn farther between 25 the rolls.

From the construction so far described it will be seen that I have provided means for automatically releasing the pressure on the 30 pressure rolls and for instantaneously positively separating the rolls.

Mounted on the extended portion 5' of the lower pressure roll shaft 4 is a driving member 40 herein shown in the form of a pulley 35 40 having a hub portion 41 provided with an annular groove at its inner end as shown at 43, the end wall of the groove being provided with a recess 44 adapted to receive a pin 45 secured in the shaft 4 for locking 40 the driving member to the shaft so that the shaft can be rotated through the medium of the driving member, and I preferably instead of a pulley 40, provide the driving member with a detachable crank as shown 45 in dotted lines at 46 in order to allow the machine to be operated manually. The opposite end of the hub 41 of the driving member 40 is annularly recessed as shown at 47 forming a seat for a coil spring 47' which 50 surrounds the outer portion of the extension 5' of the shaft 4 and is inclosed by a cap nut 48 working on the extreme threaded end of the shaft, said cap nut extending over the hub portion in such a manner that the 55 driving member is free to move longitudinally outwardly on the extension 5' of the shaft for the purpose hereinafter fully described. The inner end of the hub which is provided with a groove is rounded or beveled 60 as shown at 42 for the purpose hereinafter fully described.

The releasing member 33 is provided with depending legs having enlarged portions 49 provided with inclined faces 50 and flat 65 faces 51 which are adapted to coöperate with

the rounded inner end 42 of the hub portion 41 of the driving member 40 when the releasing member is raised by the separation of the rolls so as to move the driving member longitudinally on the extension 5' of the lower pressure roll shaft, which disconnects the driving member from the shaft so as to shut off the power instantaneously with the releasing of the pressure and the separation of the rolls, whereby the rotation of the rolls are stopped which prevents any foreign object from being drawn farther between the rolls and at the same time the rolls are free to rotate independent of the driving member so as to allow clothes which may be wound upon either pressure roll to be unwound by simply pulling on the clothes. As the releasing member 33 is carried upward by the raising of the upper pressure roll the trip member, releasing the spring catches, the inclined face 50 engages the rounded end of the driving member and forces the same outwardly and on the continuous upward movement of the releasing member 33 the flat faces 51 are brought into longitudinal alinement with the inner end of the hub of the driving member in order to form a thrust bearing as the driving member continues to rotate though disengaged from the shaft 5'. 70 75 80 85 90 95

In the operation of the wringer as herein shown and described by adjusting the trip members 36 on the operating members 32 and 33 the device can be set so that the trip members will engage the spring catches and release the pressure before the power is disconnected or they can be adjusted so that the operating members will be moved vertically a sufficient distance so as to allow the power to be disconnected before the pressure is released and I have found in practice that the best results can be obtained by adjusting the trip members on the operating members into such position that in the vertical movement of the operating members the power will be disconnected before the pressure is released, but in either case the operation of the pressure release and power control is so close together that they are practically simultaneous. 100 105 110 115

The hub 41 is provided with a threaded bore 52 carrying a set screw 53 which can be forced into engagement with the shaft of the lower pressure roll when the clutch pin 43 is out of the seat 44 of the driving member so as to lock the driving member to the lower shaft in order to enable the shaft to be rotated when the rolls are in separated position which allows the wringer to be used for wringing blankets or other thick 120 125 goods.

In connection with the automatic means for releasing the pressure, separating the rolls and the cutting-off of the power, I provide manually operated means for releas- 130

ing the spring catches which when operated throws the various parts of the machine into the same position in which they are thrown by the automatic releasing means. The 5 manually operating means consists of a pair of pivoted levers 54 and 55 mounted on the side bars 2 of the wringer frame adjacent their upper ends carrying cross bars 56 and 57 arranged under the free ends of the spring 10 catches 28 in such a manner that when the levers 54, and 55 are oscillated upon their pivots the spring catches will be engaged by the cross bars 56 and 57 so as to throw the stop lugs out of engagement with the 15 keeper pins 30 which instantaneously releases the top bar and allows the lifting springs to separate the rolls and in the separation of the rolls the releasing member 33 is carried upwardly by the upper pressure 20 roll shaft 7 so as to bring the inclined faces thereof into engagement with the hub of the driving member so as to cut off the power. The upper ends of the levers 54 are connected together by a chain 58 arranged in 25 a convenient position to be actuated by the operator of the machine, thus providing protection from injury as hereinbefore described.

From the foregoing description it will be 30 seen that I have provided an automatic pressure release and power cut-off which will operate automatically or can be operated manually, and in connection with a machine constructed as shown and described, I provide means for locking the various parts in 35 such position that the wringer can be used as an ordinary wringer so that the manual and automatic means are prevented from being operated, and to accomplish this I 40 pivotally mount on the upper end of each of the side bars 2 of the wringer frame a bail 59 which is adapted to embrace the ends of the top bar so as to rigidly secure the top bar in position within the frame in such a 45 manner that it cannot move vertically therein to release the pressure whereby the parts are allowed a slightly free movement without releasing the pressure or the cut-off of the power.

50 In the modification shown in Fig. 8 I show the application of my improved construction of releasing member for cutting off the power to a wringer having outside gears inclosed in a casing in which 60 indicates a frame, 61 and 62 the pressure rolls, and 63 the gear casing inclosing the meshing gears not shown. The releasing member 64 carrying the usual trip member 65 which is provided at its lower end with a returned-bend portion 66 having inclined faces 67 adapted to engage the rounded inner end of the hub portion of a driving member 68 so as to move the driving member longitudinally on the shaft in order to throw the clutch

pin out of the seat so as to allow the driving 65 member to rotate freely on the shaft.

In the modification shown in Fig. 9, I provide a bearing 70 formed of a casting having integral studs 71 adapted to coöperate with the springs for raising the upper 70 pressure roll which construction eliminates the use of a pin which can be readily placed over the shaft of the upper pressure roll and slid into position within the side bars of the frame. 75

In the modification shown in Fig. 10, 72 indicates a side bar of the wringer frame having a vertical bore to receive a contraction spring 73 which is provided at its upper end with an internally threaded sleeve 74 80 held within the convolutions of the spring by friction. Mounted on the top of the side bar 72 over the bore is a washer 75 through which extends an adjusting screw 76 working in the internally threaded sleeve 74 to enable 85 the tension of the spring to be adjusted.

I claim:

1. In a machine of the kind described, the combination with pressure rolls and pressure means for said rolls, a power control 90 for said rolls, and means actuated automatically by the separation of said rolls for releasing said pressure and for moving said power control to neutral position.

2. In a clothes wringer, the combination 95 with pressure rolls and pressure means for said rolls, means for holding said rolls in contact under pressure, a power control for said rolls, means for raising one of said rolls when the pressure is released therefrom, operating members actuated by the separation of said rolls having means for shifting said power control, and trip members carried by said operating members for releasing said pressure holding means, said 105 trip members being adjustably mounted upon said operating members for allowing said power control to be shifted before the pressure is released.

3. A clothes wringer, comprising pressure rolls and pressure means for said rolls, means for holding said pressure means in predetermined position, means for bodily raising one of said rolls, a power control, operating members actuated by the abnormal separation of said rolls, said operating members having means for shifting said power control, and adjustable trip members mounted on said operating members for releasing said pressure holding means after 110 the power has been disconnected. 115

4. A clothes wringer, comprising pressure rolls and pressure means for said rolls, means for bodily raising one of said rolls, means for holding said pressure means in 120 predetermined position, a power control for said rolls, operating members actuated by the separation of said rolls, means carried 125

5 by said operating members engaging said power control on the vertical movement thereof, and trip members adjustably mounted on said operating members engaging said pressure holding means for releasing said pressure means after said power has been disconnected from said roll.

10 5. A clothes wringer, comprising a frame having pressure rolls and pressure means for said rolls, a power control for said rolls, means for holding said pressure means in predetermined position, means for raising one of said rolls, and means actuated by the abnormal separation of said rolls for releasing said pressure retaining means, and for simultaneously moving said power control to neutral position.

20 6. A clothes wringer, comprising a frame having pressure rolls and pressure means for said rolls, one of said pressure rolls being provided with a drive shaft, a driving member having a connection with said shaft, means for holding said pressure means in predetermined position, and means actuated by the abnormal separation of said rolls for releasing said pressure retaining means and simultaneously disconnecting said driving member from the pressure roll shaft.

30 7. A clothes wringer, comprising a pair of pressure rolls having means for holding said rolls in contact under pressure, means for bodily separating one of said rolls when the pressure is released therefrom, operating members actuated by the separation of said rolls, a power control, means carried by one of said operating members engaging said power control for disconnecting said power on the separation of said rolls, trip members carried by said operating members engaging said pressure holding means, said operating members mounted to operate the power control prior to the releasing of pressure.

40 8. A clothes wringer, comprising a frame having pressure rolls and pressure means for said rolls mounted therein, means for holding said pressure means in predetermined position, a driving member having a driving connection with one of said rolls, and means actuated automatically by the separation of said rolls for releasing said pressure means and simultaneously disconnecting said driving member from said pressure rolls.

50 9. A clothes wringer, comprising a frame having pressure rolls, means for holding said rolls in contact under tension, means for separating said rolls when relieved of tension, a drive member having a driving connection with one of said rolls, operating members actuated by the abnormal separation of said rolls, one of said operating members having means for disconnecting said driving member, said operating members having adjustable trip members adapted to

release said pressure means after said driving member has been disconnected.

10 10. A clothes wringer, comprising a pair of pressure rolls having means for holding said rolls separated, pressure means for holding said pressure rolls in contact under pressure, a driving member having a driving connection with one of said rolls, operating members actuated by the abnormal separation of said rolls for releasing said pressure holding means, one of said operating members having means for disconnecting said driving member from said roll on the separation thereof.

15 11. A clothes wringer comprising a frame having pressure rolls and pressure means for said rolls mounted therein, a driving member having a driving connection with one of said rolls, movable members for holding said pressure means in predetermined position, means for separating said rolls relieved of pressure, and means actuated automatically by the abnormal separation of said rolls engaging said movable retaining members for automatically releasing the pressure and for disconnecting said driving member from said roll.

20 12. A clothes wringer, comprising a frame having pressure rolls and pressure means for said rolls mounted therein, a top bar movably mounted in said frame, pressure means disposed between said top bar and one of said pressure rolls, movable members carried by said top bar having a connection with said frame for holding said pressure means in predetermined position, means for bodily separating said rolls when relieved of pressure, and means actuated by the abnormal separation of said rolls engaging said retaining means for releasing the pressure on said rolls to allow said means to bodily separate said rolls.

25 13. A clothes wringer, comprising a frame having pressure rolls and pressure means for said rolls mounted therein, a top bar movably mounted in said frame having means for adjusting said pressure means, means for holding said top bar in said frame, means for bodily separating said rolls when said top bar is released, and means actuated by the abnormal separation of said rolls for releasing said top bar to allow said means to bodily separate said rolls.

30 14. A clothes wringer, comprising a frame having pressure rolls and pressure means for said rolls mounted therein, a top bar movably mounted in said frame having means for adjusting said pressure means, movable members carried by said top bar for holding said top bar in predetermined position within said frame, means disposed within said frame for bodily raising one of said rolls when the pressure is released therefrom, and members actuated automatically by the abnormal separation of said rolls en-

gaging said movable members for releasing said top bar.

15. A clothes wringer, comprising a frame having pressure rolls and pressure means for said rolls mounted therein, a top bar movably mounted in said frame having movable latches for holding said top bar in predetermined position within said frame, means disposed within said frame for bodily separating one of said rolls when the pressure is released therefrom, a driving member having a driving connection with one of said rolls, and members actuated by the abnormal separation of said rolls engaging said movable latches and said driving member for instantaneously releasing the pressure and disconnecting said driving member from said roll.

16. A clothes wringer, comprising a frame having pressure rolls and pressure means for said rolls mounted therein, a top bar movably mounted in said frame, movable latches carried by said top bar for holding said top bar in predetermined position therein, springs disposed within said frame for bodily separating one of said rolls when the pressure is released therefrom, and members actuated by the abnormal separation of said roll engaging said latches for releasing said top bar.

17. A clothes wringer, comprising a frame having pressure rolls and pressure means for said rolls mounted therein, a driving member having a driving connection with one of said rolls, and means actuated by the abnormal separation of said rolls for disconnecting said driving member from said roll.

18. A clothes wringer, comprising a frame having pressure rolls and pressure means for said rolls mounted therein, a driving member having a driving connection with one of said rolls, and means released by the abnormal separation of said rolls for bodily separating said rolls and for disconnecting said driving member.

19. A clothes wringer, comprising a frame having pressure rolls and pressure means for said rolls mounted therein, a driving member having a driving connection with one of said rolls, members carried by the upper pressure roll having inclined faces engaging said driving member on the separation of said rolls for disconnecting said driving member from said rolls.

20. A clothes wringer, comprising a frame having pressure rolls and pressure means for said rolls mounted therein, a top bar movably mounted in said frame, latches carried by said top bar, spaced pins carried by the frame of the wringer adapted to be engaged by said latches for holding said top bar in adjusted position, means for bodily raising one of said rolls, and means actuated by the abnormal separation of said rolls en-

gaging said latches for releasing said top bar.

21. A clothes wringer, comprising a frame having pressure rolls and pressure means for said rolls mounted therein, a top bar movably mounted in said frame having means for adjusting said pressure means, catches carried by said top bar for holding said top bar in predetermined position within said frame, springs arranged within said frame for bodily separating said rolls when the pressure is released therefrom, and operating members carried by the shaft of one of said rolls engaging said latches on the abnormal separation of said rolls for releasing said top bar.

22. A clothes wringer, comprising a frame having pressure rolls and pressure means for said rolls mounted therein, a top bar movably mounted in said frame, spring catches carried by said top bar for holding said top bar in predetermined position within said frame, springs arranged within said frame for bodily raising the upper pressure roll when the pressure is released therefrom, operating members carried by the upper pressure roll engaging said latches on the abnormal separation of said rolls for releasing said pressure means, and stop pins arranged in the path of travel of said latches for limiting the upward movement of said top bar.

23. A clothes wringer, comprising a frame having pressure rolls and pressure means for said rolls mounted therein, springs arranged within the side bars of said frame for bodily raising the upper pressure roll, means for holding said pressure means in predetermined position, a driving member having a driving connection with the shaft of one of said rolls, and operating members carried by the shaft of the upper pressure roll having means for releasing the pressure and disconnecting said driving member on the abnormal separation of said rolls.

24. A clothes wringer, comprising a frame having slotted side bars, pressure rolls and pressure means for said rolls mounted in said frame, said side bars having vertical bores, springs disposed within said bores having a connection with the upper pressure roll shaft, a top bar movably mounted in said frame having means for adjusting said pressure means, spring catches carried by said top bar for holding said top bar in predetermined position within said frame, and operating members engaging said spring catches on the abnormal separation of said rolls for releasing said top bar.

25. A clothes wringer, comprising a frame having pressure rolls and pressure means for said rolls mounted therein, means for holding said pressure means in predetermined position, coil springs disposed within said frame for bodily separating said rolls when

the pressure is released therefrom, operating members having a connection with the upper pressure roll for releasing said pressure means on the abnormal separation of 5 said rolls, a driving member mounted on the shaft of one of said rolls, and means carried by said operating members for disconnecting said driving member from said roll.

26. A clothes wringer, comprising a frame 10 having slotted side bars, pressure rolls and pressure means for said rolls mounted in said frame, a top bar movably mounted in the slots of the side bars having means for adjusting said pressure means, keeper pins 15 arranged across the slots of said side bars, spring catches carried by said top bar engaging said keeper pins for holding said top bar in predetermined position within said frame, operating members carried by the 20 shaft of one of said pressure rolls having trip members engaging said catches on the abnormal separation of said rolls for moving said catches out of engagement with said stop pins for releasing said top bar.

25 27. A clothes wringer, comprising a frame having pressure rolls and pressure means for said rolls mounted therein, means actuated automatically by the abnormal separation of said rolls for releasing said pressure 30 means and bodily separating said rolls, and a driving member for one of said rolls having a driving connection therewith adapted to be disconnected therefrom on the separation of said rolls.

35 28. A clothes wringer, comprising a frame having slotted side bars and provided with vertical bores communicating with the slots thereof, a pair of pressure rolls mounted in the slots of said side bars, bearings carried 40 by the shaft of the upper pressure roll, springs mounted in the bores of the side bars of said frame having a connection with said bearings for bodily raising said roll, pressure means for said rolls, means for holding 45 said pressure means in predetermined position, and means actuated by the abnormal separation of said rolls coöoperating with said retaining means for releasing the pressure on said rolls.

50 29. A clothes wringer, comprising a frame having pressure rolls and pressure means for said rolls mounted therein, a top bar movably mounted in said frame having means for adjusting said pressure means, means for holding said top bar in predetermined position within said frame, means actuated automatically by the abnormal separation of said rolls for releasing said top bar, and means for locking said top bar positively within 55 said frame so as to hold said pressure rolls in contact under pressure.

30. A clothes wringer, comprising a frame having pressure rolls and pressure means for said rolls mounted therein, a top bar movably mounted in said frame having spring 65

catches for holding said top bar in predetermined position therein, a driving member mounted on the shaft of one of said pressure rolls, operating members carried by the shaft of the upper pressure roll, trip members adjustably carried by said operating members adapted to engage the spring catches on the abnormal separation of said rolls for releasing said pressure means, said operating members having inclined faces engaging 70 75 said driving member on the separation of said rolls for disconnecting said driving member from the shaft of said roll.

31. A clothes wringer, comprising a frame having slotted side bars, pressure rolls and pressure means for said rolls mounted in said frame, a top bar movably mounted in said frame, spaced pins extending across the slots of said side bars, spring catches carried by said top bar engaging one set of pins for holding said top bar in predetermined position within said frame, means for bodily separating said rolls when pressure is released therefrom, and means actuated by the abnormal separation of said rolls for moving 80 85 said latches out of engagement with said pins for releasing said pressure means, said latches engaging the other set of pins for limiting the upward movement of said top bar.

32. A clothes wringer, comprising a frame having pressure rolls and pressure means for said rolls mounted therein, means for normally holding said pressure means in predetermined position, a spring pressed driving member mounted on the shaft of one of said pressure rolls having a driving connection therewith, and operating members carried by the shaft of the other pressure roll for releasing said pressure means on the abnormal separation of said rolls, said operating members having means for dis-engaging 95 said driving member from the shaft of said roll.

33. A clothes wringer, comprising a frame having pressure rolls and pressure means for said rolls mounted therein, a top bar movably mounted in said frame having means for adjusting said pressure means, springs disposed within said frame for raising the upward pressure roll when the pressure is released therefrom, spring catches carried by said top bar for holding said top bar in predetermined position therein, operating members carried by the shaft of the upper pressure roll, trip members adjustably mounted on said operating members having inclined faces engaging said spring catches on the abnormal separation of said rolls for releasing said top bar, a driving member having a driving connection with one of said rolls, one of said operating members having inclined faces engaging said driving member for disconnecting said driving member on the separation of said rolls.

34. A clothes wringer, comprising a frame having side bars provided with vertical bores and longitudinal slots communicating with said bores, a pair of shafts mounted in 5 the slots of said side bars carrying pressure rolls, bearings secured on the upper pressure roll carrying shaft, springs mounted on said bearings, a top bar movably mounted in said frame having means for adjusting said 10 springs, means for holding said top bar in predetermined position within said frame, springs disposed within the bores of said

side bars having a connection with the bearings of the upper pressure roll shaft, and means actuated by the abnormal separation 15 of said rolls for releasing said top bar for allowing said springs to bodily raise the upper pressure roll.

In testimony whereof I hereunto affix my signature in the presence of two witnesses. 20

EDGAR B. STOCKING.
